(57) **CLAIM**

The ornamental design for an ear plug, as shown and described.

DESCRIPTION

FIG. 1 is a front perspective view of an ear plug, showing my new design;

FIG. 2 is a top plan view thereof;

FIG. 3 is a side elevational view thereof;

FIG. 4 is a bottom plan view thereof; and,

FIG. 5 is a cross-sectional view thereof, taken along the 5—5 line of FIG. 2, whereas the dashed lines are for environmental purposes only and form no part of the claimed design.
